UNITED STATES PATENT OFFICE

GEORGE CROMER OAKES, OF PASO ROBLES, CALIFORNIA

HEEL PROTECTOR

Application filed February 5, 1929. Serial No. 337,666.

This invention aims to provide a simple means for protecting the heel of a stocking so that the heel of the stocking will not be worn out as it works up and down with the 5 foot of the wearer in an article of footwear.

It is within the province of the disclosure to improve generally and to enhance the utility of devices of that type to which the invention appertains.

10 With the above and other objects in view, which will appear as the description proceeds, the invention resides in the combination and arrangement of parts and in the details of construction hereinafter described and 15 claimed, it being understood that, within the scope of what is claimed, changes in the precise embodiment of the invention shown can be made without departing from the spirit of the invention.

20 In the accompanying drawings:—

Figure 1 shows in longitudinal section, a device of the class described, mounted in an article of footwear, a part of the article of foot-wear being broken away;

25 Figure 2 is a top plan wherein a part of the article of foot-wear has been broken away;

Figure 3 is a cross section on the line 3—3 of Figure 2.

In the drawings there is shown an article 30 of footwear including a sole 1 and an upper 2. In combination with the article of foot-wear, there is provided a heel protector made of any desired flexible material, such as cloth, light leather, or textile material of any sort. The 35 heel protector includes a body 3 and a sole 4 connected to the lower end of the body. The body 3 is shaped to fit upon the sides 5 of the upper 2 and to extend across the back 6 of the upper.

40 The top edge of the body 3 is turned outwardly and downwardly to form a wing 7 and to form a roll 8 joining the wing 7 to the body 3. Stitching, shown at 9, may constitute the means for securing the wing 7 to 45 the upper 2.

The roll 8 is yieldable to permit the body 3 to move up and down a little with the heel of the wearer, but the stitching 9 holds the upper portion of the body 3 against crawling up or crawling down under the action of the 50 heel of the wearer.

The sole 4 of the protector projects beyond the body 3 to form a tongue 10 whereby the instep of the foot of the wearer will tend to hold down the lower portion of the body 3 55 when the heel of the wearer moves up and down, the aggregate result being that, although the back part of the protector can move up and down with the heel of the wearer, there is no creeping upwardly, creeping 60 downwardly, or wrinkling, the protector always embracing the heel of the wearer evenly and smoothly.

The device is simple in construction and inexpensive to make, and it can easily be built 65 into a shoe at the time the shoe is made, although the protector may be put in as a repair job. The protector will replace the lining now in use, it being a matter of practical knowledge that such linings usually pull 70 away after the shoes have been worn for a short time.

What is claimed is:—

The combination with an article of foot-wear including a sole and an upper, of a heel 75 protector including a body and a sole connected to the lower end of the body, the body being shaped to fit upon the sides of the upper and to extend across the back of the upper, the top edge of the body being turned outwardly and downwardly to form a wing and a roll joining the wing to the body, and means for securing the wing to the upper, the roll being yieldable and the space between the upper and the wing on the one hand, and the body on the other hand being unencumbered to permit the body to move up and down a little, with the heel of the wearer, said means holding the upper portion of the body 80 against crawling up or crawling down under 85 90

the action of the heel of the wearer, the sole of the protector projecting forwardly beyond the body of the protector to form a tongue, whereby the instep of the foot of the wearer will tend to hold down the lower portion of the body, when the heel of the wearer moves up and down between the tongue and the place where the wing is secured to the upper as aforesaid.

10 In testimony that I claim the foregoing as my own, I have hereto affixed my signature.

GEORGE CROMER OAKES.
